UNITED STATES PATENT OFFICE.

ADOLPH W. SCHRAMM, OF RIVERTON, NEW JERSEY, ASSIGNOR TO ELECTRO DENTAL MANUFACTURING COMPANY, OF PHILADELPHIA, PENNSYLVANIA, A CORPORATION OF PENNSYLVANIA.

CHAIR.

1,268,886.

Specification of Letters Patent. Patented June 11, 1918.

Application filed June 15, 1917. Serial No. 174,828.

To all whom it may concern:

Be it known that I, ADOLPH W. SCHRAMM, a citizen of the United States, residing at Riverton, in the county of Burlington and 5 State of New Jersey, have invented a new and useful Improvement in Chairs, of which the following is a specification.

My invention relates to an improvement in chairs such as those used by dentists, 10 surgeons, barbers, etc., and which are adapted to be adjusted vertically. And the invention involves more particularly the use of fluid or liquid in chambers in the base or pedestal of the chair placed under pressure 15 by some outside source of pressure supply, preferably air or water.

I have provided means whereby the chair, or the plungers supporting the seat of the chair having been raised, may be held in 20 such adjusted position, even though there may be a leakage of fluid from the chamber in which the fluid is confined. I have also provided means whereby with the plungers in 25 elevated position should it be desired to further elevate the plungers, this may be done without any backward slip of the plungers. Also, I have provided means whereby should 30 the load be removed from the chair, there will be no tendency of the plungers to move upwardly. I have also provided means whereby the plungers supporting the platen to which the chair seat is secured are brought 35 to rest automatically at both limits of travel.

In the accompanying drawings, Figure 1 40 is a sectional elevation of the chair pedestal, showing the valve mechanism for controlling the circulation of the liquid in the operation of the chair; Fig. 2 is a part sectional elevation of the fluid valve; Fig. 2^a is a sectional view of the valve, taken at A—A of Fig. 2; Figs. 3 and 4 are part sectional elevation views of the mechanism for controlling and operating the fluid and liquid valves; Fig. 5 is a plan view showing the 45 general arrangement of the pedals by which the valves are operated and their connection to the valves; and Fig. 6 is a section taken through the liquid and fluid valves.

Like characters designate like parts in all 50 the figures.

Referring to the drawings in detail, and particularly to Figs. 1 and 2, P designates a casting forming part of the base of pedestal for the chair. This base has a central col-

umn 1 forming a chamber, within which 55 liquid is confined. Within this chamber is a hollow plunger 2 guided at its upper end by a bearing 3. On the lower end of this plunger 2 is a piston 18. Carried within the plunger 2 and keyed thereto is a hollow plunger 5 secured to the platen 6, which latter carries the seat of the chair. Screwed into the lower end of the plunger 5 is a plug 7. Screwed into the plug 7 is a member 8, packing 9 being provided between the plug 65 7 and this member. The lower end of the member 8 is shaped so as to form a chamber 10 beneath the plunger 5, this chamber communicating with the interior of the column 1 by ports 11. A port is formed in the member 8 forming a communication between the chamber 10 and the interior of the plunger 5. This port is controlled by a rod 12 screwed into the member 8. The plunger 5 is partially filled with some liquid, preferably 70 oil. The chamber which is formed by the space left between the inside of the column 1 and the outside of the plunger 2 is completely filled with the liquid, a member 4 carried by the plunger 2 forming the bottom 75 of this chamber. A reservoir 13 is formed in the pedestal P, this reservoir communicating by way of passage 14, port 15, chamber 35, port 16 and passage 17, with the chamber 18^a under the piston 18 of the plunger 2. Communicating with the reservoir 13 by way of passages 19 and 20 is a pressure 80 supply pipe 21, controlled by valve mechanism, the operation of which will admit fluid 85 under pressure to the reservoir 13. 90

The fluid valve mechanism and the liquid valve mechanism will now be described. The fluid valve comprises a hollow valve stem 22 entering the valve casing 23 and having 95 movement vertically therein.

The lower end of the valve stem 22, as viewed in Fig. 2, has an annular head 24 seated by a spring 25 on a valve seat 24^a. This valve controls the supply of fluid to the passages 19 and 20 and therefore to the 100 reservoir 13. Carried within the valve stem 22 and passing through the head 24 is another stem 26 adapted to be moved vertically therein by means of mechanism which will be hereinafter described. The valve stem 26 105 has a cross section shaped as shown in Fig. 2^a. The lower end of this valve stem 26 carries a valve head 27 which is seated on

the annular head 24 by means of a spring 28, one end of the spring bearing against the top of the valve stem 22 and its other end against a projection of the valve stem 26.

5 As will be seen from Fig. 2^a, if the valve stem 26 be forced downwardly, as viewed in Fig. 2, fluid in the reservoir 13 is free to escape by way of passages 20 and 19 and the grooves 29 cut in the valve stem 26, the

10 upper end of these grooves extending beyond the top of the valve stem 22, or in other words being open to the atmosphere.

The liquid valve mechanism is best illustrated in Fig. 1 and comprises a stem 30, the lower end of which is attached to a lever 31, the latter being pivotally attached to a member 32 shown attached to the casting forming pedestal P. The ends of the member 32 hold in place yokes 33 and 34, forming guides for the valve stems 36 and 37, these stems carrying valves 38 and 39 respectively. The valves are seated by springs 40 and 41. The valve stems 36 and 37 pass through the lever 31. Longitudinal movement of the rod 30 in one direction will lift valve 38 against the action of its spring 40 to open the port 15, the valve 39 remaining closed. Movement of the rod 30 in the opposite direction will cause the valve 39 to 50 lift against the action of its spring 41 to open the port 16, the valve 38 in this instance remaining closed. The rod 30 is guided in the casting P forming the pedestal of the chair.

55 The fluid valve described and the liquid valve mechanism is adapted for operation by means of pedals 42 and 43 (see Figs. 4 and 5). A crosshead 44 serves to actuate the valve stems 22 and 26 of the fluid valve and the rod 30 for operating the liquid valves. The crosshead 44 is mounted upon a rod 45 guided by a casting 46. The pedals 42 and 43 form parts of the lever 51, the latter being operatively connected to the

45 crosshead 44 by the shaft 52, lever 50, and link 49. Pressure on the pedal 42 will cause the link 49 and therefore the crosshead 44, to be moved upwardly as viewed in Fig. 4, carrying with it rod 45 whose lower head will cause the sleeve 48 to move upwardly, compressing a spring 53 as shown in Figs. 3 and 4. As soon as pressure is taken off the pedal 42, the pedal and the crosshead 44 will be returned to normal position by expansion of the spring 53. Pressure on the pedal 43 will cause the crosshead 44 to be moved in the opposite direction to that just described, forcing the sleeve 47 downwardly and again compressing the spring 53. If 60 pressure is taken off the pedal 43, the pedal and the crosshead 44, etc., will be returned to normal position by expansion of the spring 53.

I have also provided brake mechanism 65 for holding the seat of the chair in position

as regards its horizontal rotation. This brake mechanism, which I will now describe, may be operated through either one of the pedals 42 or 43 without, however, effecting any movement of the fluid and air valves. 70

Referring now to Figs. 1, 3, 4, and 5, the brake mechanism comprises a lever 54 engaging a brake shoe 56, which engages the plunger 2. The lower end of the lever 54 is connected by a nut 55 and a link 60 screwed thereinto, and a member 57, to a rod 58, the latter being adapted to have vertical movement in a guide member 59 secured to the pedestal P of the chair. The lower end of the rod 58 engages the crosshead 44 so that any movement of the crosshead 44 will be transmitted to the brake shoe 56, through the several links, etc., just described. In order that the crosshead 44 may be moved by means of either pedal 42 or 43 without 85 imparting movement to the fluid and liquid valve mechanisms, I have provided lost motion between the ends of the crosshead 44 and the valve stems 22 and 26 of the fluid valve, and the rod 30 of the liquid valve. 90

With the parts in the position shown in Fig. 1, the operator may depress the pedal 42 and cause the crosshead 44 to be moved upwardly. This upward movement of the crosshead 44 actuates the valve stem 22 to 95 cause the annular head 24 and valve head 27 carried thereby to be moved upwardly and permit fluid to enter to the reservoir 13 by way of pipe 21 and passages 19 and 20. The upward movement of the crosshead 44 also 100 causes the rod 30 of the liquid valve mechanism to be moved upwardly. This movement of the rod 30 carries the lever 31 about its pivot to lift the valve 39 from its seat and open port 16. As soon as the pressure 105 in the reservoir 13, due to the admission of fluid under pressure thereto has risen sufficiently, the valve 38 will be lifted from its seat against the action of the spring 40, opening the port 15. The liquid in the reservoir 13 may now flow therefrom through the port 15, chamber 35, port 16, and by way of passage 17 beneath the piston 18. As soon as the pressure in the liquid has risen sufficiently to overcome the inertia of the plungers 2 and 5 and their load, the plungers will move upwardly. As the plunger 2 moves upwardly, it forces the fluid out of the column 1 by way of ports 11 to the chamber 10 beneath the plunger 5, and the latter will be moved upwardly relatively to the plunger 2, carrying with it, of course, the platen 6 of the chair seat. After the chair seat has been moved upwardly sufficiently, the operator removes his foot from the pedal 42, the fluid valve will be closed, and the liquid valve mechanism will be returned to central position by the spring 53 in the manner already described, and the valves 38 and 39 will be seated by their respective springs. 115 120 125 130

The chair will now be held stationary with the liquid locked. If now it be desired to move the chair upwardly still farther, the pedal 42 may be depressed as before, to open 5 the fluid valve and admit pressure to the chamber 13, at the same time opening the liquid valve 39. If at this time the pressure in the reservoir 13 is not sufficient to move the plungers upwardly, the plungers 10 may not move downwardly by reason of the fact that the valve 38 cannot open the port 15 until the pressure under the valve is greater than that above it, the latter pressure being due to the weight of the plungers 15 and their load. When the pressure in the reservoir 13 has risen above that in the chamber 35, the valve 38 will open and the plungers will move upwardly and may then be brought to rest as before by merely releasing the pedal 42. Should the operator 20 fail to remove his foot from the pedal 42, the plungers 2 and 5 will merely be moved upwardly until the ports 11 in the plunger 2 are closed off automatically by the top of the 25 chamber in the column 1; this closing off being gradual, the plungers will be gradually brought to rest, without appreciable shock or jar. If it be desired now to lower the chair seat, the operator depresses the 30 pedal 43 to actuate the cross-head 44 in the opposite direction to that just described. This movement of the crosshead will move the valve stem 26 downwardly against the action of the spring 28, carrying with it the 35 valve head 27. At the same time, the valve 38 will be lifted off its seat to open the port 15. Fluid may now escape from the reservoir 13 by way of passages 20 and 19, up through the grooves 29 in the valve stem 26 and to the atmosphere. As soon as the pressure has 40 dropped sufficiently, the weight of the plungers and their load will lift the valve 39 from its seat to open port 16, and fluid is now free to flow from beneath the piston 18 by way 45 of passage 17, ports 16 and 15 to the reservoir 13. As the plunger 2 descends, the plunger 5 descends relatively thereto; liquid from beneath the plunger 5 being free to escape by way of the ports 11 to the 50 chamber in the column 1. The chair may be allowed to descend to any desired position and may then be stopped by merely taking the pressure off the pedal 43, and the valve mechanism will be returned to central position 55 by means of the spring 53, and the valves 38 and 39 will be seated by their respective springs.

Inasmuch as, with the chair stationary the ports 15 and 16 are closed by the valves 38 and 39, should the load be taken off the chair, the chair, or rather to be more exact, the plungers 2 and 5 cannot move upwardly, as any expansion of the air or other fluid in the reservoir 13 due to the removal of the weight 60 from the plungers, while it might be suf-

ficient to lift the valve 38, still, fluid would be prevented from flowing to beneath the plungers, by reason of the fact that the valve 39 would be in position to close off the port 16. Should a person of comparatively 70 light weight seated in the chair be replaced by one of heavier weight, the extra load on the plungers 2 and 5 will not cause them to settle, by reason of the fact that while this extra weight may be sufficient to cause the 75 valve 39 to lift off its seat, the valve 38 would be more firmly seated to close off the port 15 and thus prevent any flow of fluid back to the reservoir 13.

Any air which may find its way to the 80 chamber in the column 1, may be exhausted therefrom by raising the plungers 2 and 5 by hand, unscrewing the rod 12 and then allowing the plungers to settle back into place by their own weight. The liquid in the plunger 85 5 will flow into the chamber in the column to fill it up, and the air will be forced out and through the liquid in the plunger 5 where it may escape to the atmosphere through the bottom of the platen 6. 90

From the foregoing description it will be seen that I have provided an apparatus of the class described which is very simple in construction, positive in action, and which to be operated requires practically no exertion on the part of the operator. 95

What I claim as new and desire to secure by Letters Patent of the United States is:—

1. In an adjustable chair, supporting means for the seat of the chair, a fluid chamber, a pressure supply for placing a fluid in said chamber under pressure to actuate the chair seat supporting means, a valve controlling said pressure supply, ports for the passage of the fluid, valves controlling said 100 ports, operating means for said first and second named valves, and means operating automatically to center said operating means and to cause the said last-named valves to close off their ports simultaneously. 105

2. In an adjustable chair, supporting means for the seat of the chair, a fluid chamber, a pressure supply for placing a fluid in said chamber under pressure to actuate the chair seat supporting means, ports for the 110 passage of the fluid, valves controlling said ports, operating means for said valves, means for actuating said operating means to neutral position automatically and the valves into position to close said ports simultaneously, one of said valves maintaining its port closed to maintain the chair seat supporting means in adjusted position should the pressure on the fluid due to the weight of the chair seat and its load exceed that due 115 to the pressure supply. 120

3. In an adjustable chair, supporting means for the seat of the chair, a fluid chamber, a pressure supply for placing a fluid in said chamber under pressure to actuate 130

the chair seat supporting means, ports for the passage of the fluid, valves controlling said ports, operating means for said valves, means for actuating said operating means 5 to neutral position automatically and the valves into position to close said ports simultaneously, one of said valves maintaining its port closed to maintain the chair seat supporting means in adjusted position should 10 the pressure on the fluid due to the weight of the chair seat and its load be less than that due to the pressure supply.

4. In an adjustable chair, supporting means for the seat of the chair, a fluid chamber, a pressure supply for placing a fluid in said chamber under pressure to actuate the chair seat supporting means, ports for the passage of the fluid, valves controlling said ports, operating means for said valves, 15 whereby one valve may be moved off its seat while the other remains seated, until the pressure on the fluid due to the pressure supply is sufficiently high to lift said last named valve to cause the chair to ascend or 20 descend as desired, and means for actuating said operating means to neutral position automatically and the valves into position to close said ports simultaneously.

5. In an adjustable chair, supporting means for the seat of the chair, a fluid chamber, a pressure supply for placing a fluid in said chamber under pressure to actuate the chair seat supporting means, ports for the passage of the fluid, valves controlling 35 said ports, means for operating either of said valves at will the other maintaining its port closed until it is lifted by the pressure on the fluid to either raise or lower the chair seat supporting means, and means for actuating said operating means to neutral position automatically and the valves into position to close said ports simultaneously.

6. In an adjustable chair, supporting means for the seat of the chair, a fluid chamber, a pressure supply for placing a fluid in said chamber under pressure to actuate the chair seat supporting means, valve mechanism for controlling said pressure supply, ports for the passage of the fluid, valves 45 adapted to close said ports simultaneously, a common operating means for the first and second named valves, whereby the supporting means for the seat of the chair may be elevated or lowered at will, and means 50 for automatically returning said operating means to neutral position and the valves into position to close said ports simultaneously.

7. In an adjustable chair, supporting means for the seat of the chair, a fluid chamber, a pressure supply for placing a fluid in said chamber under pressure to actuate the chair seat supporting means, a valve for controlling the admission of pressure to said 55 fluid chamber, a valve carried by said first-

named valve and having movement relatively thereto for controlling the discharge of pressure from said fluid chamber, and valve mechanism coöperating with said pressure supply and exhaust valves and controlling the passage of the fluid to and from said fluid chamber in adjusting the chair seat supporting means. 70

8. In an adjustable chair, supporting means for the seat of the chair, a fluid chamber, a pressure supply for placing a fluid in said chamber under pressure to actuate the chair seat supporting means, a valve, having a hollow stem for controlling the admission of pressure to said fluid chamber, 80 a valve having a stem extending into the stem of the first-named valve for controlling the discharge of pressure from said fluid chamber, and valve mechanism coöperating with said pressure supply and exhaust 85 valves and controlling the passage of the fluid to and from said fluid chamber in adjusting the chair seat supporting means.

9. In an adjustable chair, supporting means for the seat of the chair, a fluid chamber, a pressure supply for placing a fluid in said chamber under pressure to actuate the chair seat supporting means, and a valve having a hollow stem for controlling the admission of pressure to the said fluid chamber, a valve having a stem extending into the stem of the first-named valve and having movement relatively thereto for controlling the discharge of pressure from said fluid chamber, and valve mechanism coöperating with said pressure supply and exhaust 95 valves and controlling the passage of fluid to and from said fluid chamber in adjusting the chair seat. 100

10. In an adjustable chair, supporting means for the seat of the chair, a fluid chamber, a pressure supply for placing a fluid in said chamber under pressure to actuate the chair seat supporting means, a valve having a hollow stem for controlling the admission of pressure to said fluid chamber, a valve having a stem extending into the stem of the first-named valve and having movement relatively thereto for controlling the discharge of pressure from said fluid chamber, grooves in the stem of said last named valve by which pressure may escape from the fluid chamber to the atmosphere, a head on said valve stem engaging the first named valve and preventing the escape of 110 pressure by way of said grooves, and valve mechanism coöperating with said pressure supply and exhaust valves and controlling the passage of fluid to and from said fluid chamber in adjusting the chair seat. 115

11. In an adjustable chair, supporting means for the seat of the chair, a fluid chamber, a pressure supply for placing a fluid in said chamber under pressure to actuate the 120 fluid chamber, a valve carried by said first-

chair seat supporting means, valve mechanism controlling said pressure supply and the passage of the fluid, brake mechanism for preventing rotation of the supporting means for the chair seat, actuating means for said brake, a further movement of which in the same direction will actuate the valve mechanism, the brake being operable, however, without any motion being imparted to the valve mechanism.

12. In an adjustable chair, supporting means for the seat of the chair, a fluid chamber, a pressure supply for placing the fluid in said chamber under pressure to actuate the chair seat supporting means, valve mechanism controlling said pressure supply, ports for the passage of the fluid, valves controlling said ports, means connecting said valves, actuating means for said valves, comprising a pedal mechanism pivoted intermediate its ends, one end being depressed to adjust the chair seat in one direction, and the opposite end being depressed to adjust the chair seat in the opposite direction.

13. In an adjustable chair, supporting means for the seat of the chair, a fluid chamber, a pressure supply for placing a fluid in said chamber under pressure to actuate the chair seat supporting means, valve mechanism controlling said pressure supply, valves for controlling the passage of the fluid to and from said fluid chamber, yokes for supporting said last named valves, and means for operating the pressure supply valve mechanism and one of the fluid valves simultaneously.

14. In an adjustable chair, supporting means for the seat of the chair, a fluid chamber, a pressure supply for placing a fluid in said chamber under pressure to actuate the chair seat supporting means, valves controlling said pressure supply, valves for controlling the passage of the fluid, and means for selectively controlling one or the other of the pressure supply valves and a corresponding fluid valve to elevate or lower the chair seat supporting means as desired.

15. In an adjustable chair, supporting

means for the seat of the chair, a fluid chamber, a pressure supply for placing a fluid in said chamber under pressure to actuate the chair seat supporting means, valve mechanism controlling said pressure supply, valves for controlling the passage of the fluid, a bell crank lever connecting the stems of the last named valves, means for operating the pressure valve mechanism and the fluid valve mechanism simultaneously, and means attached to one arm of the bell crank lever for connecting the fluid valves to the operating means therefor.

16. In an adjustable chair, supporting means for the seat of the chair, a fluid chamber, a pressure supply for placing a fluid in said chamber under pressure to actuate the chair seat supporting means, valve mechanism controlling said pressure supply, valves for controlling the passage of the fluid, a bell crank lever connecting the valve stems of the said last named valves adapted to lift one valve from its seat while the other remains seated, and a common operating means for operating the pressure supply and fluid valve mechanism simultaneously, said operating means being connected to said bell crank.

17. In an adjustable chair, supporting means for the seat of the chair, a fluid chamber, a pressure supply for placing a fluid in said chamber under pressure to actuate the chair seat supporting means, valve mechanism controlling said pressure supply, valves controlling the passage of the fluid, springs for seating the last named valves so as to maintain them closed at the same time, and operating means for all of said valve mechanism whereby the pressure supply valve mechanism may be operated to admit pressure to the fluid chamber or discharge it therefrom as desired at the same time lifting one or the other of the fluid valves, the other remaining seated under the action of its spring.

In testimony whereof I have hereunto set my hand.

ADOLPH W. SCHRAMM.
